UNITED STATES PATENT OFFICE.

FELIX LOWY, OF MILWAUKEE, WISCONSIN, ASSIGNOR TO THE PALMOLIVE COMPANY, OF MILWAUKEE, WISCONSIN, A CORPORATION OF WISCONSIN.

DESIGN FOR A CARTON.

61,371.

Specification for Design.

Patented Aug. 15, 1922.

Application filed July 9, 1920. Serial No. 395,163. Term of patent 7 years.

To all whom it may concern:

Be it known that I, FELIX LOWY, a citizen of the United States, residing at Milwaukee, in the county of Milwaukee and State of Wisconsin, have invented a new, original, and ornamental Design for a Carton, of which the following is a specification, reference being had to the accompanying drawing, forming part thereof.

The figure is a perspective view of a carton, in accordance with the design.

I claim:

The ornamental design for a carton, as shown.

FELIX LOWY.
